UNITED STATES PATENT OFFICE.

ALEXIS P. STEELE, OF STATESVILLE, NORTH CAROLINA.

DRAG-LINE EXCAVATOR.

Application filed August 18, 1921. Serial No. 493,342.

To all whom it may concern:

Be it known that I, ALEXIS P. STEELE, a citizen of the United States, and a resident of Statesville, in the county of Iredell and 5 State of North Carolina, have invented a new and useful Improvement in Drag-Line Excavators, of which the following is a specification.

The present invention relates to drag line 10 excavators for digging and loading clay or other earthy material and has for an object the arrangement and positioning of the sheaves through which the cable supporting the bucket operates so that the path 15 of travel of the cable from the operating drum mechanism to the end of the boom shall have as few turns as possible during the several operations, thus preventing wear and tear in the cable and effecting a saving 20 of power.

Another object of my invention is to position the sheaves so as to prevent a downward pressure on the boom base. In excavators of this type, heretofore, the sheaves 25 have been supported by a post carried by the turn-table, the cables operating in the sheaves cause a downward pressure on the boom base, which pressure renders the turning of the boom harder to accomplish.

Another object of my invention is to 30 provide means whereby the lifting and the operating cables operate between pairs of sheaves carried by the A frame and the turn-table respectively when the boom operates directly forward, and means whereby 35 each of said cables operate through a sheave in said pairs respectively when the boom is swung to the one side and thru the other sheave in said pairs when the boom is swung 40 to the other side, and means whereby the said cables can pass from one sheave to the other.

The present invention is illustrated in the accompanying drawings, in which—

Figure 1 shows a side elevation with a 45 portion of the frame structure broken away so as to show the sheaves and turn-table in clear view.

Figure 2 shows a front elevation with the 50 boom projecting to one side.

Figure 3 is a top plan view showing the turn-table and boom projecting straight forward and a dotted outline of the boom when operating at an angle to the longitudinal 55 line of the machine.

Figure 4 shows a top plan view of the turn-table and drum operating the turn-table with a portion of the upper surface of the turn-table removed showing the operating cable. 60

Figure 5 shows a front elevation of a modification of my invention with the boom projecting to one side.

Similar characters of reference are used to designate corresponding parts. 65

In the drawings as shown in Figures 1 and 2, I have shown the excavator 1 mounted upon a suitable base or carrier 2 which also serves as a combined base or carriage for the operating drums 3 and the engine 4. 70 In order to move the excavator from place to place and into position for digging and loading clay or other material, the carriage 2 is mounted upon side rollers 5. To afford a smooth path of travel for the rollers 5, 75 planks 6 are laid down in advance of the traveling machine. After the excavator has passed over the planks, these can be taken up and relaid in advance of the moving machine. When the excavator is in operative position the carriage 2 is additionally supported by the blocks 7, one on each side thereof at the forward end and by the built up support 8 under the center of the machine and extending longitudinally thereof. 80 This support can be of any suitable structure.

Supported by the base is a derrick frame 10 which carries the sheaves or pulleys. The derrick 10 may be of any convenient 90 structure and as shown is an A frame with vertical braces 13 and horizontal brace member 21 and a guy rope 17 secured to bracket 50 at the peak. The sheave 14 is pivotally mounted on the peak of the A frame through 95 which operates cable 18 supporting the boom 23 at the end 19 and midway of its length at 20. The sheaves 11 and 12 are pivotally mounted on the cross-brace 21 on pivot pins 22. The cross-brace 21 is reinforced by braces 16. The axes of the sheaves 11 and 12 project inward and to the rear and a plane passing through each of said sheaves perpendicular to their axes respectively will be at an angle to the horizontal, 100 longitudinal and transverse lines of the excavator.

The sheaves thus positioned are in the plane of the cable 25 extending from the drum mechanism 24 to the sheave 26 mounted on the end of the boom 23. When 105 110

the boom 23 is swung to the left, the cable 25 will operate through the sheave 12 and the plane passing through the cable and sheave 12 will be at right angles to the axis of revolution of the sheave 12. Likewise when the boom is swung to the right, cable 25 will operate through the sheave 11 and the plane passing through the cable and the sheave will be at right angle to the axis of the revolution of the sheave 11. It will be readily seen from the drawings that if the boom operates directly forward in the direction of the longitudinal medial line of the machine, cable 25 will operate free of the sheaves 11 and 12 and will have a straight path of travel from the drum 24 to the sheave 26 situated at the forward end of the boom. The boom 23 is mounted on the turn-table 27 which in turn is pivotally mounted on the frame 30. The upper surface of frame 30 has a broad bearing surface 28 to accommodate the under bearing surface of the turn table 27 and the downward pressure of the base of the boom. The periphery of the turn-table is grooved to accommodate the actuating cable 31. This cable is operated by drum 43, the ends of the cable being secured in the groove 29 of the turn-table 27 at 33 adjacent the cut out portion 37. Between the turn-table and the drum 43, cable 31 passes around pulleys 32 mounted in bracket 35. This arrangement of the cable as shown in Figures 3 and 4 will afford the boom an operating space in front of the excavator approximately a half circle.

Supported by the cross-brace 21 are the guide blocks 51 and 52 which slope inwardly and are parallel to the plane of the sheaves 11 and 12 respectively and which support the cable 25 when the said cable is slack and operate as a guide to position the cable in the groove of the sheave 11 or 12 when the boom is swung to the side on which the respective sheave is positioned.

A conventional bucket 40 with bar 53 is raised or lowered by the cable 25 the bar 53 being secured to the bucket 40 by chains 54, said bucket being retained in a horizontal position by a slight tension on the cable 39 secured to the one end of the bar 53 and to the bucket 40 by the chain 55. The primary purpose of the cable 39, however, is to load the bucket 40 by dragging the same inwardly, the teeth 41 engaging and digging into the earth, thus loosening and causing the broken clods to be forced into the bucket. The inner end of the cable 39 is secured to the drum 42 and is wound on said drum when the bucket is dragged inwardly. The cable 39 operates through the sheaves 44 and 45 which are pivotally mounted on the turn-table 27 on the pivot pins 47 and 48 respectively. It will be understood that when the boom is swung to

the right or left the cable 39 will operate through the sheave positioned respectively on the right or left side of the excavator.

In order to position the cable 39 in the groove of the sheave 44 or 45, I have provided a guide block 15 carried by the turn-table 27 and which supports the cable when the said cable is slack and operates to position the cable in the groove of the sheave 44 or 45 when the cable is under tension.

In loading the bucket, I have found it convenient to position the cable 39 in a plane passing vertically through the center of the boom. For this purpose, I have pivotally mounted a sheave 49 in the cut-out portion 37 of the turn-table. The roller 46 secured to the boom operates to retain the cable in alignment with the groove in the wheel of the sheave 49.

In Figure 5 I have shown a modification of my invention which is similar to the construction shown in Figures 1 and 2 with the exception that the sheaves 11^a and 12^a carried by the cross-brace 21^a of the A frame operate in a horizontal plane. A sheave 53^a carried by the boom operates to direct the cable 25^a into alignment with the sheave 11^a or 12^a when the boom is turned to the one side or the other respectively.

In my invention I employ any suitable motor power for operating the excavator but which is preferably a double drum hoisting device and a vertical stationary engine as illustrated in the drawings. A roof 9 protects the drum mechanism and engine from the weather.

I claim—

1. In a machine of the class described, in combination, a boom mounted to swing, an operating cable associated with said boom, means for operating said cable, a pair of sheaves between which said cable passes, said sheaves being arranged in planes of rotation at an angle with each other and guide means in front of said sheaves for positioning the cable in the groove of either sheave.

2. In a machine of the class described, in combination, a boom mounted to swing, an operating cable associated with said boom, means for operating said cable, a pair of sheaves between which said cable passes, said sheaves being arranged in planes of rotation at an angle with each other and at an angle to the horizontal transverse line of the machine and guide blocks between the sheaves and the boom end for positioning the cable in the groove of either sheave.

3. In a machine of the class described, in combination, a boom mounted to swing, an operating cable associated with said boom, means for operating said cable, a pair of sheaves between which said cable passes, said sheaves being arranged in planes of rotation at an angle to the horizontal trans-

- verse line of the machine and at an angle to the horizontal longitudinal line of the machine and at an angle to each other and sloping guide blocks arranged to position 5 the cable in the groove of either one or the other of the sheaves.
4. In a machine of the class described, in combination, an A frame, a pair of sheaves lying in planes of rotation at an 10 angle with each other and at an angle to the horizontal longitudinal line of the ma-
- chine, a boom mounted to swing, an operating cable associated therewith, means whereby said cable operates through one of said sheaves when the boom operates at one side 15 and through the other of said sheaves when the boom operates on the other side, and sloping guide blocks operating to pass the said cable, from the one sheave to the other when the boom is turned from the one side to the 20 other.

ALEXIS P. STEELE.
